UNITED STATES PATENT OFFICE.

WILLARD O. FRENCH, OF CLINTON, WASHINGTON.

HOOD FOR FIREARM-SIGHTS.

986,376.

Specification of Letters Patent.

Patented Mar. 7, 1911.

Application filed February 25, 1910. Serial No. 545,938.

To all whom it may concern:

Be it known that I, WILLARD O. FRENCH, a citizen of the United States of America, residing at Clinton, in the county of Island 5 and State of Washington, have invented new and useful Improvements in Hoods for Fire-arm-Sights, of which the following is a specification.

This invention relates to hoods for fire 10 arm sights, and has for an object to provide a hood which is especially designed for use in connection with the rear sight of a rifle and associated with respect thereto to shield it to an extent from such light reflections 15 that might tend to mar the purpose of the sight and render it objectionable in accurately sighting the front sight.

In the drawing, forming a portion of this 20 specification and in which like numerals of reference indicate similar parts in the several views:—Figure 1 is a detail side elevation of a portion of a rifle showing my improved hood applied to the rear sight thereof. Fig. 2 is a transverse section taken on 25 the line 2—2 of Fig. 1. Fig. 3 is a detail perspective view of the hood.

My improved hood is designed particularly for use in connection with the rear sight upon the well known Winchester rifle 30 but it is obvious that it is adapted for use in connection with rifles or other fire arms in which front and rear sights are employed. The rifle 1 herein shown has its barrel provided with a rear sight 3, the same being 35 of such construction that it may be adjusted in a vertical plane and also in a plane longitudinally of the barrel. The member 4 or those portions of the side edges of the member 4 which extend outwardly beyond the 40 sides of the top surface of the barrel, as shown at 4^a in which the slide or sight piece 3 is mounted is provided with arcuate edge portions or portions of any other suitable configuration which will permit convenient 45 and quick attachment of the hood 5 to the barrel. The hood 5 is preferably formed from a single piece of sheet material, preferably metal, and as shown, the material is

stamped to provide longitudinally extending side walls 6 whose lower edges are bent 50 to form inwardly directed flanges 7 which are adapted to fit beneath the arcuate edges of the member 4. The side walls 6 of the hood are connected by a top member or crown 8 which extends longitudinally of the 55 barrel and is disposed immediately above the sight piece or slide 3 in suitable spaced relation thereto. A retaining and stop-forming screw 9 is operatively connected with the side walls 6 of the hood and is 60 adapted for operation to move the walls toward each other and into clamping engagement with the arcuate surfaces of the said member 4.

The hood 5 as herein shown and described 65 is extremely simple in construction and it may be applied readily to the barrel of a fire arm of any form where it is desired to exclude the light from the sight. The use of the article when associated with the rear 70 sight excludes to a desired extent such light rays as would tend to blur the vision of the shooter and prevent his accurately finding the front sight. In associating the hood with the rear sight the former is moved onto 75 the barrel from the rear thereof until the adjusting screw abuts against the sight, after which the screw is adjusted to hold the hood operatively applied to the barrel.

I claim:

The combination with a barrel and a sight 80 therefor, the said sight including a member whose side edges extend beyond the sides of the upper surface of the barrel, of a hood detachably engaged with the barrel and comprising a member having a crown portion above the sight and disposed longitudinally of the barrel, and spaced side portions extending downwardly at the sides of the sight and formed at their lower edges to provide 85 longitudinal clamping flanges for engagement beneath the said outwardly extending side portions of the member of the sight, and a combined clamping and stop forming screw passing through the said side portions 90 of the hood and adjustable therein to move 95

the side portions to a position to cause the flanges thereof to be clamped against the said outwardly extending side portions of the member of the sight, the said screw being 5 designed to engage the member to limit the movement of the hood in one direction on the barrel.

In testimony whereof I affix my signature in presence of two witnesses.

WILLARD O. FRENCH.
